OIL TANK FOR MOTORCYCLE

Kenneth H. Watkins, Los Angeles, Calif.
(16053 Vanowen St., Van Nuys, Calif. 91406)

Filed Aug. 12, 1966, Ser. No. 3,450

Term of patent 14 years

(Cl. D90—8)

The dominant features of the design reside in the portions shown in full lines.

I claim:

The ornamental design for an oil tank for motorcycle, substantially as shown and described.
